UNITED STATES PATENT OFFICE.

CLARENCE HERVY FROELICH, OF BETHLEHEM, PENNSYLVANIA, ASSIGNEE TO
BETHLEHEM STEEL COMPANY, OF BETHLEHEM, PENNSYLVANIA.

GUN CARRIAGE.

Application filed August 8, 1925. Serial No. 49,049.

This invention relates to wheeled gun carriages and more particularly to the type of such carriages provided with two separable trail members adapted to be spread apart to function as anchor means to give the carriage stability when the gun is fired, and having an equalizing bar connecting said members adapted to support the base upon which the top carriage is mounted, so that the stresses of recoil shall be transmitted equally to the trail members regardless of the uneven state of the ground.

Heretofore, it has been proposed to construct a wheeled gun carriage provided with two separable trail members adapted to be spread apart to function as anchoring means and having an equalizing bar seated thereon to support the base upon which the gun carriage is mounted. The trail members have been hinged to sleeves which are rotatably mounted on the axle and fixed against axial movement. In this prior construction, the equalizing bar is made telescopic and elongates as the trail members are spread apart so as to maintain a seat and be supported by said members. When the trail members rest in different planes and the gun is fired in azimuth there is a great tendency for the carriage to swing out of position due to the sliding connection between the equalizing bar and the trail members. Such a condition necessitates the relaying of the gun before subsequent firing and furthermore does not obtain rigid support necessary to oppose the firing forces.

An object of the invention is to provide a wheeled gun carriage in which the trail members are rigidly held in spaced relation in the vertical plane through the axis of the equalizing bar at all positions of said members.

Another object of the invention is to provide a simple jointed connection between the equalizing bar and each of the trail members so that the parts may articulate with respect to each other without relative sliding engagement in the longitudinal direction of said bar, when said members are in the firing position.

Another object of the invention is to provide a wheeled gun carriage in which the trail comprises two members which are supported on the axle and adapted to be spread apart to function as anchoring members when the gun is to be fired, said members being supported in close proximity to the wheels when

in their closed or traveling position so as to oppose lateral strains on the axle when traveling, due to the unevenness of the ground, and said members being further adapted to be supported in close proximity to the axial plane of the gun when in the firing position to oppose the resultant firing forces.

The present invention comprises generally a pair of trail members hinged to sleeve members which are rotatably and slidably mounted on the gun axle. A rigid equalizing bar centrally supports the base for the top carriage upon which the gun is mounted. The equalizing bar is connected to each of the trail members by means of swivel joints. When it is desired to spread the trail members apart to support the carriage in firing position, said members swivel about the equalizing bar and the sleeve members slide towards each other on the axle and in this manner the fixed distance between the trail in a plane through the points of support of the equalizing bar is maintained and provides a rigid support for the gun carriage.

The novel features will be more fully understood from the following description and claims, taken with the drawings, in which:

Fig. 1 is a plan view of a gun carriage embodying the invention;

Fig. 2 is a partial plan view illustrating the supporting frame for the gun and top carriage;

Fig. 3 is a cross sectional view taken on line III—III in Fig. 4;

Fig. 4 is a cross sectional view taken on line IV—IV in Fig. 2;

Fig. 5 is a cross sectional view taken on line V—V in Fig. 2;

Fig. 6 is a bottom plan elevation of the hinged end of the trail member.

Referring now to the drawings, 10 represents the wheels of a gun carriage having an axle 11. Sleeves 12 are revolvably and slidably mounted on the axle and are limited in their axial movement, in the outward direction, by the fixed collars 13, provided in close proximity to the hub portions of the wheels and, in the inward direction, by the abutment faces of a base member 14, which are revolvably mounted on the axle.

The base member 14 is provided with an extended spindle or pivot portion 15, upon which is revolvably and slidably mounted a cross member 16. The trail members 17 are hinged at 18 with respect to the sleeves 12

and they are provided each with a vertical slideway 19 adapted to receive the split bearing block 20. The ends of the cross member 16 are spherical, as at 21, and are adapted 5 to be received in the spherical bearing 22 formed in the block 20, which is made, preferably, in two parts. The block 20 is adapted to slide in its respective slideway constrained by a coil spring interposed between the abutment member 23 and the upper face of said 10 member 16.

An opening 24 is provided in the base member 14 to receive the pintle of the top carriage which supports the cradle and gun mechanism, these parts, not being part of the invention, are not shown and described in detail.

While the trail members are being spread apart to the broken line position, shown on 20 Fig. 2, they swivel on the cross member 16, and the sleeves 12 slide axially on the axle 11 into contiguity with abutment faces 14' of the base member, to provide a support for the axle near the point of greatest flexure 25 when said axle is subjected to firing stresses, the hinged connections at 18 and the sliding connection of the cross member 16 with respect to the pivot portion of the base member 14 permitting such movement.

30 It will be seen that when the trail members are spread and anchored to the ground, a rigid supporting frame is provided, regardless of irregularities in the ground surface or the position of the wheels, and that the 35 trail members are rigidly braced by the cross member to resist lateral forces occasioned when the gun is fired.

When the trail members are brought together into their traveling position, the sleeve members 12 are contiguous with the collars 13, and the trail members are, therefore, supported on the axle in close proximity to the 40 wheels. With this construction, the supporting frame constitutes a truss structure 45 connected to the axle near its extremities and which therefore serves to strengthen or reinforce the latter. This is particularly advantageous when the gun travels over uneven ground.

50 While I have shown my invention in but one form, it will be obvious to those skilled in the art that it is not so limited, but is susceptible of various other changes and modifications without departing from the spirit 55 thereof, and I desire, therefore, that only such limitations shall be placed thereupon as are imposed by the prior art or as are specifically set forth in the appended claims.

Having thus described the invention what 60 I claim as new and desire to secure by Letters Patent is:

1. In a frame for a wheeled gun carriage having an axle, the combination of anchoring members revolvably and slidably mounted 65 on the carriage axle, a base member for a

top carriage, and a member revolvably mounted on said base member and engaging the anchoring members in order that the frame may conform to the ground independent of the position of the wheels of the gun 70 carriage.

2. In a frame for a wheeled gun carriage having an axle, the combination of anchoring members revolvably and slidably mounted on the carriage axle, a base member mounted 75 on said axle, and a member revolvably mounted on said base member and having articulated connections with respect to the anchoring means in order that the frame may conform to the ground independent of the 80 position of the wheels of the gun carriage.

3. In a wheeled gun carriage having an axle, the combination of a pair of anchoring members revolvably and slidably mounted on the carriage axle, a cross member jointed 85 to each of said first named members intermediate the ends thereof, and a base member supported on the axle and on the cross member.

4. In a wheeled gun carriage having an 90 axle, the combination of a pair of anchoring members revolvably and slidably mounted on the carriage axle, a cross member jointed to each of said first named members, and a base member hinged to the axle and supported 95 on the cross member.

5. In a wheeled gun carriage having an axle, the combination of a pair of anchoring members slidably mounted on the carriage axle, a cross member jointed to each of said 100 members, and a base member supported on the axle and on said cross member.

6. In a wheeled gun carriage having an axle, the combination of trail members 105 mounted on the carriage axle, a base member mounted on said axle, a cross member mounted on said base member and having spherical ends, and socket bearings for said ends carried by the trail members, said socket bearings being permanently spaced from 110 each other by the cross member.

7. In a wheeled gun carriage having an axle, the combination of trail members mounted on the carriage axle, a base member 115 mounted on said axle, a cross member mounted on said base member and having ends shaped to constitute elements of swivel joints, vertical slideways formed in each of said trail members, a second element of a swivel joint mounted in said slideways and adapted to receive the first mentioned joint 120 element, and means to yieldingly prevent sliding movement between said second element and its associated trail member.

8. In a wheeled gun carriage having an 125 axle, the combination of trail members mounted on the carriage axle, a base member mounted on said axle, a cross member mounted on said base member, a vertical slideway formed in each of said trail members and 130

adapted to receive said cross member, and means to yieldingly prevent sliding movement between said cross member and said trail members.

5 9. In a wheeled gun carriage having an axle, the combination of trail members mounted on the carriage axle, a base member mounted on said axle, a cross member mounted on said base member and having terminal spherical bearing portions, and adjustable socket bearing portions carried by the trail members to engage said terminal bearing portions.

10 10. The combination, with a gun having a wheel-supported axle, of a supporting frame comprising a pair of sleeve members adapted to be revolvably and slidably mounted on the axle, a trail member pivoted to each of said sleeve members, a base member having a journal member adapted to engage the axle, a spindle carried by the base member, an equalizing member pivotally mounted on the spindle, and articulated connections between the equalizing member and the trail members.

15 11. In a wheeled gun carriage having an axle, the combination of a pair of sleeve members revolvably mounted on the carriage axle and having limited axial sliding movement thereon, a trail member pivoted to each sleeve member, a base member hinged to said axle, an equalizing bar revolvably mounted on said base member, and a swivel joint connection between said bar and each of said trail members.

20 12. The combination, with a gun carriage having an axle and a base member journaled on the axle, of a split trail comprising sleeve members movable on the axle, a spindle carried by the base member and extending transversely of the axle, a pair of trail members, hinged connections between the respective sleeve and trail members, a cross member journaled on the spindle, and universal connections between the ends of the cross mem-

ber and intermediate portions of the trail members.

25 13. The combination, with a gun carriage having an axle and a base member journaled on the axle, of a split trail comprising sleeve members movable on the axle, a spindle carried by the base member and extending transversely of the axle, a pair of trail members, hinged connections between the respective sleeve and trail members, a cross member journaled on the spindle, and ball and socket connections between the ends of the cross member and intermediate portions of the trail members.

30 14. The combination, with a gun carriage having an axle and a base member journaled on the axle, of a split trail comprising sleeve members movable on the axle, collars carried by the axle adjacent to the wheels and co-operating with the base member to limit axial movement of the sleeves, a spindle carried by the base member and extending transversely of the axle, a pair of trail members, hinged connections between the respective sleeve and trail members, a cross member journaled on the spindle, and universal connections between the ends of the cross member and intermediate portions of the trail members.

35 15. In a split-trail device for a gun carriage, said carriage including a wheeled axle and a gun supporting member, the combination, of laterally slideable guide members on the axle, of trail members having at their forward ends articulated connections to the guide members ground anchoring means at their rear ends and fulcra intermediate between said connections and anchoring means, and of spacing means pivotally associated with the gun supporting member and with the fulcra of the trail arms, to maintain said fulcra in radial equi-distance from the longitudinal axis of the gun supporting member.

40 In testimony whereof I hereunto affix my signature this seventeenth day of July, 1925.

CLARENCE HERVY FROELICH.
